CLAIM

The ornamental design for a night vision telescope, as shown and described.

DESCRIPTION

FIG. 1 is a front perspective view of a night vision telescope;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a rear perspective view thereof;
FIG. 9 is a bottom perspective view thereof;
FIG. 10 is an enlarged fragmentary view of a left corner portion of the front view shown in FIG. 2;
FIG. 11 is an enlarged fragmentary view of a portion above a center-left portion of the front view shown in FIG. 2;
FIG. 12 is an enlarged fragmentary view of a center-left portion of the front view shown in FIG. 2;
FIG. 13 is an enlarged fragmentary view of a left corner portion of the rear view shown in FIG. 3; and,
FIG. 14 is an enlarged fragmentary view of a central top portion of the rear view shown in FIG. 3.

The broken lines shown in FIGS. 1-14 depict environment and form no part of the claimed design.
